UNITED STATES PATENT OFFICE.

ENOCH OHNSTRAND, OF KENMORE, NEW YORK.

HINGED COMPRESSOR.

Application filed November 20, 1926. Serial No. 143,777.

This invention relates to trays or filing drawers of the kind customarily used to hold ledger cards or sheets for reference or for removal for the purpose of inserting additional data thereon, and more particularly to improved locking means for clamping the cards within the tray during its transportation, as for example between its cabinet and the desk of a clerk.

10 The invention resides in the novel construction and arrangement of elements set forth in the following specification and includes the provision of simple yet effective locking or clamping means adapted to secure the ledger 15 cards within the tray but permitting a full inspection and ready removal of the cards when desired, and the further provision of means permitting such inspection or removal without disturbing the adjustment of one 20 element of the clamping means.

In general the invention comprises a tray of the ordinary type, a follower movable lengthwise of the tray and adjustable to a variety of positions, and a compressor plate 25 for clamping the ledger cards against the follower, having a double hinged connection to the front end of the tray and an actuating bail associated therewith adapted to be lowered to compress the plate against the cards 30 or to be raised permitting the plate to tilt forwardly against the tray end.

One embodiment of the invention is illustrated in the accompanying drawings, in which—

35 Fig. 1 is a central longitudinal section of a tray showing the compressor plate in rearward clamped position, in solid lines, and in its most forward position, in broken lines;

40 Fig. 2 is a transverse section on the line 2—2 of Fig. 1, with portions of the device in elevation;

Fig. 3 is a front elevation of the device showing an intermediate position of the compressor plate; and

45 Fig. 4 is a broken central longitudinal section of Fig. 3.

The ledger tray 5 preferably consists of a substantially rectangular box of sheet metal, open at the top and having a bottom wall 6 50 with bent up portions 7 constituting side walls of the tray, a front wall 8 and rear wall 9 permanently joined to the side walls and bottom wall by rivets passing through side and bottom flanges 11 and 12 respectively. The 55 bottom of the tray may be provided with a false bottom consisting of longitudinal side

panels 13 and a central channel strip 14 having turned flanges 15 extending lengthwise of the tray. Retaining flanges 16 riveted to the front and rear walls of the tray secure 60 the false bottom against removal or displacement.

The compressor 17, a thin, flat plate of sheet metal, is mounted for swinging movement upon a double hinge consisting of three transverse hinge leaves, the outer leaves 18 and 20 being riveted to the false bottom adjacent the front wall and to the lower edge of the compressor plate 17, respectively, and the center leaf 19, of appreciable width, constituting 65 a freely swinging leaf member or toggle between the hinges 21 and 22, extending transversely of the tray, by which it is pivotally connected to the leaves 18 and 20 respectively, the hinge 22 being positioned adjacent the lower edge of plate 17.

In the compression position of the plate 17, shown in solid lines in Fig. 1, the center leaf 19 and hinge member 22 lie flatwise upon the upper surface of the false bottom panels 80 19, permitting the lower edge of the compressor plate to rest adjacent said false bottom. The compressor plate is locked in this position by means of the bail member 23 which is preferably a U-shaped metal rod of suitable stiffness and strength having outwardly bent ends 85 24 engaging socket members 25 mounted upon the upper edge of the front wall 8, which may be strengthened by a reinforcing strip. The cross-bar portion 26 of bail 23 slides vertically of the compressor plate within guide straps 27 fastened to the forward face thereof at either end, but in said operated position the side portions of the bail incline downwardly toward the plate 17 so that the cross-bar 26 90 abuts the lower shoulders of the straps 27 in a horizontal plane below the plane of the bail ends 24, thus effectively locking the plate in its compressed position. The side arms of the bail are preferably of such length that in 95 said position the top of the compressor plate is inclined rearwardly of the tray.

When the tray is in use for the purpose of consulting or removing the ledger cards, the compressor plate occupies its extreme forward position, inclined against the front wall of the tray, as shown in broken lines in Fig. 1. In this position, the central hinge leaf 19 is upwardly inclined from hinge 21, the cross bar of the bail abuts the upper shoulders of 100 the straps 27, and the lower strap shoulders 105 rest upon the upper edge of front wall 8,

thus preventing accidental dislodgment of the compressor plate.

The aforesaid change in position is accomplished by first lifting one of the side arms 5 of the locking bail 23 and then carrying the plate 17 upwardly and forwardly by grasping a convenient bent over handle 28 at its upper edge. To restore the compressor plate to its former position, it may be tilted rearwardly on hinge 21 and then locked by forcibly depressing the bail, thereby concomitantly carrying the central hinge leaf 19 downwardly, or the plate may be moved rearwardly and downwardly through substantially 15 parallel planes, until the leaf 19 rests upon the bottom, before depressing the locking bail. This intermediate position of the movable elements, in which the compressor plate is tilted forwardly upon the hinge 22, against 20 the bail 23, is best shown in Fig. 4. It is obvious that the operated position of the bottom edge of the compressor plate is then fixed, and that the locking operation may be completed by depressing the bail 23, as before.

25 Cooperating with the compressor plate to lock the ledger cards 29, a second flat plate or follower 30, adapted to support the cards from the rear, is mounted to slide lengthwise of the tray upon guides riding within the bottom channel strip 14. Although, any ordinary type of follower, such as is customarily employed in filing cabinets, may be utilized for this purpose, the follower illustrated in the drawings is highly efficient and simple 30 of operation. The plate 30 is provided at its lower edge with a rearwardly extending flange 31 so disposed as to slide upon or slightly above the bottom panels 13 of the tray. Secured to the under side of flange 31 35 and extending at right angles to the plate 30 are flanged guide members 32 adapted to slide against the side walls of channel 13 beneath the inturned flanges 15 thereof so that the plate 30 is held and steadied in its 40 movement along the tray.

45 In order that the follower may be fastened in any desired position within the tray, the side flanges 33 of a locking pawl 34 are pivoted by any suitable means to either side of a 50 U-shaped member 35 fixed to the rear surface of the plate 30 upon its bottom flange 31. The upper end of the pawl is bent to form a convenient operating grip and the lower end thereof extends downwardly within the channel 14 to meet the bottom thereof in frictional locking engagement. The pawl is normally held in such engagement, preventing movement of the follower, by means of a spring 36 secured at one end to the member 35 and engaging the free end of the pawl at a point 60 above its pivot. To release the locking engagement of the pawl, the upper end thereof is pressed toward the follower 30, thereby lifting the lower edge of the pawl from contact with the bottom of channel 14 and per-

mitting the follower to be moved lengthwise of the tray.

The follower is preferably inclined rearwardly from the bottom in substantial parallelism to the front compressor plate 17, so that by clamping a series of ledger cards against the follower all portions of the cards are compressed to the same degree, whereby they are effectively secured within the tray during its transportation from place to place even though the tray may be tipped on one side or inverted.

Although the cards may be thus clamped between the plate 17 and the follower, it is preferred that the rear surface of the compressor plate be provided with a guard plate 37 overlapping the sides of the compressor plate and extending approximately to the side walls of the tray. The guard plate is attached to the compressor plate by headed rivets 38 slidable in vertical slots 39 stamped out of the plate 17 near its respective lateral edges, in such manner that the guard 37 may slide vertically on the surface of the compressor plate, with its lower edge resting by force of gravity on the bottom panels 13 in all the adjustable positions of the compressor 90 17 and tilts with the plate 17 without lifting. The guard plate serves to strengthen the compressing members, presents a smooth flat surface against the ledger cards, protects the cards against scratching or soilage from contact with hinge 22 and also saves this hinge from bending stresses when the compressor plate is in its forwardmost position.

When it is desired to clamp the cards 20 within the tray to preserve them in better shape while not in use, or to transfer the tray to or from its storage vault or cabinet, the follower plate and double hinge are set at the intermediate position of Figs. 3 and 4 and the series of cards are moved forwardly by the released follower until the bottom edge of the foremost card is pressed against the bottom of the guard plate 37. This operation automatically fixes the ultimate position of the follower which may then be clamped by releasing the pawl 34. Depression of the bail 23 will then move the compressor plate 17 to its operated position compressing the cards against the follower and effectively locking them against accidental dislodgment. When so secured, the ledger cards are also protected against collisions which might bend or soil the card edges and said cards are also somewhat protected against fire due to their closely packed condition. The tray may be stored in a vault or filing cabinet enclosed by a sliding screen, cut out portions 40 in the front and rear walls of the tray serving as 110 convenient handles for transportation.

To free the cards for inspecting or removal the bail is unclamped as aforesaid and the compressor plate lifted and carried forwardly against the front wall 8. Since the 115 120 125 130

central hinge leaf 19 is then swung upwardly from the tray bottom, an increased longitudinal space is provided for the cards without disturbing the position of the follower.

5 This feature is very desirable when a relatively large number of cards are filed in the tray, since it permits the cards to be separated, allowing a full view of the data inscribed on the cards including the entries adjacent their bottom edges, and also permits the temporary or permanent insertion of a number of cards in the tray before the follower need be readjusted. Such readjustment is necessary only when a larger or 10 smaller number of cards are to be reclamped for storage, and the operation is easily performed by releasing the follower, setting the compressor plate to intermediate position, resetting the follower at the limit of its possible forward movement and then depressing the locking bail. Since the bail is depressed below a horizontal position, it is obvious that 15 the compressor plate is fixedly locked in its operated position.

20 25 It is thus apparent that the invention includes principally a tray for holding a group of cards or the like comprising an abutment or follower member, a compressor member for clamping the cards together and means for concomitantly tilting the compressor away from the cards and withdrawing the bottom of the compressor a predetermined distance from the cards, the upper end of the compressor being preferably spaced from the 25 cards a greater distance than the lower end, and resting upon the front end of the tray, the compressor also having an intermediate position in which the bottom of the compressor is in clamping position while the top 40 is spaced from the cards permitting the adjustment of the follower to a varied number of cards.

A ledger tray constructed in accordance with the foregoing description may be simply

45 and economically fabricated, the majority of elements being stamped from sheet metal, and possesses many novel and improved features, but, since various structural modifications may be embodied in an operable device, 50 it is not my intention that my invention be limited to the exact construction shown, except as it is defined by the following claims.

I claim:

55 1. A tray for holding a group of cards or the like comprising an abutment and a compressor for clamping the cards together, means for bodily lifting and tilting the compressor upwardly and away from the cards into a position wherein the lower end of the compressor is spaced from the cards and the upper end is spaced a greater distance therefrom, and a face plate slidably associated with said compressor so that it tilts with the compressor without lifting.

60 65 2. A filing tray having therein a com-

pressor extending transversely thereof and pivoted adjacent its lower edge for swinging movement, a double hinge having one hinge member attached to said compressor, the other hinge member fixed to the bottom portion of the tray, and a freely swinging leaf portion between said hinge members to permit the compressor to be swung upwardly from the tray bottom, and actuating means for operating said compressor movement.

70 75 3. A filing tray having therein a compressor extending transversely thereof and pivoted adjacent its lower edge for swinging movement, a hinge attached to said lower edge permitting said movement, said hinge having a freely swinging leaf portion pivoted to a second transverse hinge and said second hinge being fixed to a bottom portion of the tray near the front wall of the tray but spaced therefrom, whereby the compressor may be swung forwardly of the tray and upwardly from said bottom portion to provide greater space to the rear of the compressor, and actuating means for operating the movement of said compressor.

80 85 90 95 100 105 4. A filing tray having therein a compressor extending transversely thereof and pivoted adjacent its lower edge for swinging movement, a hinge attached to said lower edge permitting said movement, said hinge having a freely swinging leaf portion pivoted to a second transverse hinge and said second hinge being fixed to a bottom portion of the tray near the front wall of the tray but spaced therefrom, whereby the compressor may be tilted forwardly against the front wall of the tray in one position with its lower edge raised from the tray bottom and in another position may be tilted forwardly of the tray with its lower edge resting adjacent said bottom, said actuating means also operating to tilt the compressor rearwardly from said second position to lock the compressor.

110 115 120 125 5. A filing tray having therein a compressor extending transversely thereof and pivoted adjacent its lower edge for swinging movement, a hinge attached to said lower edge permitting said movement, said hinge having a freely swinging leaf portion pivoted to a second transverse hinge and said second hinge being fixed to a bottom portion of the tray near the front wall of the tray but spaced therefrom, whereby the compressor may be swung forwardly of the tray and upwardly from said bottom portion to provide greater space to the rear of the compressor, and a guard plate mounted for vertical sliding movement on the back face of the compressor so that its lower edge rests upon the tray bottom during swinging movement of the compressor, thereby protecting said hinges.

6. A filing tray having therein a compressor extending transversely thereof and

pivoted adjacent its lower edge for swinging movement, a hinge attached to said lower edge permitting said movement, said hinge having a freely swinging leaf portion pivoted to a second transverse hinge and said second hinge being fixed to a bottom portion of the tray near the front wall of the tray but spaced therefrom, whereby the compressor may be swung forwardly of the tray and upwardly from said bottom portion to provide greater space to the rear of the compressor, a bail member pivoted at its ends upon the front wall of the tray to swing up and down adjacent the front face of the compressor to cause said swinging movement thereof, and a strap attached to said compressor face for guiding and limiting said up and down movement of the bail whereby the compressor may be tilted forwardly against the front wall of the tray, said strap having a shoulder engaging the top of said wall to hold the compressor in said forward position.

7. A tray for holding a group of cards or the like, comprising an abutment, a compressor for clamping the cards together, means hingedly connected to the tray and the compressor at spaced points adapted to per-

mit movement of said compressor bodily away from said cards and relative to said tray, and means for retaining said compressor in card compressing position.

8. A tray for holding a group of cards or the like, comprising an abutment, a compressor for clamping the cards together, means for bodily elevating said compressor relative to the tray in movement from card compressing to non-compressing relation, said means permitting tilting of said compressor, means for operating and retaining said compressor in card compressing position, and means for limiting operation of the last mentioned means formed for cooperation with tray carried means to support said compressor in disengaged relation relative to the cards.

9. A tray for holding a group of cards or the like, comprising an abutment, a compressor for clamping the cards together, means for moving said compressor longitudinally and laterally relative to said cards from compressing to non-compressing position, and means interposed between the compressor and cards movable only longitudinally relative to the cards with said compressor.
